Term of patent 3½ years

(Cl. D1—12)

FIG-1

The dominant features of my design reside in the full line portion of the drawing.

The rear of the lower panel is essentially the same as the front shown, and the rear of each of the three trapezoid-shaped letter holders is substantially plain.

I claim:

The ornamental design for a sign, substantially as shown and described.
